Primary Examiner — George D. Kirschbaum*Assistant Examiner* — Ciese Moore, Jr.(74) *Attorney, Agent, or Firm* — Muncy, Geissler, Olds & Lowe, P.C.(57) **CLAIM**

I claim the ornamental design for a support member for bicycle carrier, as shown and described.

DESCRIPTION

FIG. 1 is a right, front, top perspective view of a support member for bicycle carrier showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a right, rear, bottom perspective view of the support member for bicycle carrier; and,

FIG. 9 is a right, front, top perspective view showing the support member for bicycle carrier in use.

The broken lines illustrate portions of the support member for bicycle carrier in FIGS. 1-9 and bicycle carrier in FIG. 9. These broken lines form no part of the claimed design.
